(57) **CLAIM**

The ornamental design for a rotor for an internal combustion engine, as shown and described.

DESCRIPTION

FIG. 1 is a front perspective view of a rotor for an internal combustion engine showing my new design;

FIG. 2 is a rear perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof; and,

FIG. 8 is a left side view thereof.

The rotor is attached to a shaft of the internal combustion engine. It is used to control ignition and cool the engine.
